APPARATUS FOR THE PREHEATING OF
PATTERN PLATES

Robert André Ronceray, Thiais, France

Application July 27, 1948, Serial No. 40,874
In France January 20, 1948

2 Claims. (Cl. 22—9)

1

The present invention relates to a method for pre-heating the pattern-plates used in foundry work for moulding.

It has also for its object a device which permits of preheating these plates, and finally it comprises the pattern-plates fitted with this device or adapted for the application of this method.

There exists, in foundry work, a considerable disadvantage caused by the cold in winter. It is known that the metal pattern-plates utilized are at a low temperature, and the casting sand, slightly moist, clings to the plates when in contact with them. This adherence causes sand to be ripped off in the course of the pattern removal, rendering the mould useless.

It has thus been necessary to pre-heat the pattern-plates, and, in order to do this, several more or less empirical means have been utilized.

These means consist namely, either in pre-heating the plate itself by exposing it before a source of heat, or in pre-heating the molding table of the molding machine, for instance by means of an electric resistor located within its thickness. But these methods present many drawbacks. In the last mentioned method, namely, a considerable time must elapse before the pattern-plate is heated, because the warming up first involves heating the whole mass of the table and, moreover, the pattern-plate may have a very considerable thickness. These methods are namely inadequate when moving frequently from place to place. On the other hand, the heating elements do not stand up well under the repeated jars to which they are submitted on the machine.

It is the object of the present invention to provide a method which will remedy these drawbacks and which insures an effective and controlled pre-heating under all conditions.

The method according to the invention consists substantially in causing to flow in, or in contact with the pattern-plate, a hot or previously heated fluid.

The fluid used is composed, preferably, but not exclusively, of compressed air, since the casting machines are either actuated by compressed air or fitted with a blower functioning by means of air under pressure.

The device according to the invention comprises, substantially, the combination, with a moulding or casting machine, of a pre-heating device for the fluid used, of a heat exchanging device in contact with or within the pattern-plate to be pre-heated, and of means for slowing down the expansion of the heating fluid at its exit from the device, in order to prevent it from ex-

2

panding, and to avoid, consequently, a lowering of its temperature.

It will be understood that, while remaining within the scope of the invention, it is possible to omit the particular pre-heating device if one can obtain a hot fluid which can be drained, at least in part, in order to utilize it according to the invention.

Keeping the foregoing in mind, compressed air 10 is utilized by preference as pre-heating fluid, the latter being conducted to the heating device by a suitable conduit taken on the compressed air circuit of the machine. The heat exchanger is advantageously formed by a very good heat-conducting metal tube and which is located either in a groove or slot machined on the lower surface 15 of the pattern-plate, in the case of a single pattern-plate, or sunk in the mass of the pattern-plate during its manufacture, when the pattern-plate is a double surface plate or when this pattern-plate has a considerable thickness.

In one form of embodiment of the invention which can more especially be applied to single surface pattern-plates, the heat exchanger is simply 20 constituted by a cast groove or cut, which is closed by a plate positioned between the pattern-plate and the table of the machine, so that this groove may form a conduit, in conjunction with this plate. The latter could, moreover, be made integral with the pattern-plate.

In any case, this groove, and the metal tube, 25 are given a sinuous shape, so as to insure an equal and fast distribution of the heat in the pattern-plate.

It will be noted that the replacing of a pattern-plate can be carried out almost as fast as when a pattern-plate of the usual type is utilized, since 30 it is only necessary to disconnect and re-connect a conduit, flexible by preference, conducting the hot fluid to the pattern-plate according to the invention.

The pre-heating device is advantageously formed by a heat-insulated container, within 35 which is arranged a heating system and through which passes a compressed air flow partly expanding in said container.

It is an advantage to provide deflectors in this 40 container, in order that the flowing air follows a path as long as possible around this heating organ; and thus makes a maximum utilization of the heat value.

The mentioned heating device may also be connected to the heat-exchanger, for instance by means of flexible tubes.

55 The heating device may be equipped so that it

can receive either a hot fluid such as steam, or an electric resistor either encased or not, single or multiple.

In the latter case, it is advantageous to use a two part resistor, or a resistor receiving two different voltages so as to obtain relatively strong pre-heating at the start when using a given type of pattern-plate, and to obtain a working temperature capable of maintaining the pre-heated pattern-plate at the desired temperature.

When the heating device is an electric resistor, it should be in operation, only when the heating fluid flows around it, so as to avoid overheating, which would cause possible damage.

According to the invention, a device actuated by the pressure of the flowing fluid is provided, controlling the opening or the closing of the electrical circuit. This device may be in the form of a push-member receiving on one face the action of the said fluid, and actuating either a mercury-rocking contact breaker, or a switch.

The following specification, together with the appended drawings, given as non-limitative examples, describe the invention and the characteristics which stand out from the text, as well as from the drawings, being understood as included in the invention.

Fig. 1 shows a plan view of a pattern-plate according to the invention, seen from the bottom;

Fig. 2 shows a cross-sectional view through II-II of Fig. 1;

Fig. 3 shows a plan view of a double pattern-plate according to the invention;

Fig. 4 shows a cross-sectional view through IV-IV of Fig. 3;

Fig. 5 shows a vertical cross-sectional view of one form of embodiment of an air-heater;

Fig. 6 shows a vertical cross-sectional view of a modification;

Fig. 7 shows a longitudinal cross-sectional view of another modification;

Fig. 8 shows a cross-sectional view through VIII-VIII of Fig. 7;

Fig. 9 shows a longitudinal cross-section of another form of embodiment of a pre-heater;

Figs. 10 and 11 illustrate schematically the arrangement of a pre-heater on a moulding machine;

Fig. 12 shows a partly elevational cross-sectional view of one form of embodiment comprising an automatic safety device.

Figs. 1 and 2 illustrate one form of embodiment of a pattern-plate according to the invention. This pattern-plate is constituted by a supporting plate 1 on which the pattern proper 2 is secured.

According to the invention, this plate bears a groove or slot 3, formed or milled therein according to whether the pattern-plate already exists or if it is a plate which will be cast according to the invention.

A simple slot can be made which will, later, be closed on its free surface, by an asbestos plate positioned between the supporting plate 1 and the table of the moulding machine. This asbestos plate, not shown, plays simultaneously the part of the fourth side of the conduit 3 and of thermal insulator between the pattern-plate and the table of the machine, thus preventing heat losses through the latter by heating. In this case, an intake nozzle 4 is fixed at one end of the conduit 3 at the other end of which an air flow retarding device 5 is provided. This air flow retarding device prevents the hot fluid from expanding in the conduit 3 and consequently avoids a loss of heat of this fluid.

It is also possible, in this form of embodiment, to more simply mill the conduit 3 and arrange in this conduit a metal tube 6, made of copper for instance, as illustrated partly in Fig. 1. In this case the milled or moulded conduit 3 could be filled with asbestos, in order to avoid heat losses; it is also possible to utilize the asbestos plate mentioned in the preceding paragraph. The nozzle 4 is connected by means of an air-tight flexible tube to the exit nozzle of the fluid pre-heater.

In the case illustrated in Figs. 3 and 4 where a double surface pattern-plate is used, this pattern-plate is provided with a supporting plate 7, on which the members 8 and 9 of the pattern proper are secured. In this case, it is more advantageous to provide, during the moulding of the pattern-plate, a heating circuit constituted by a metal tube 10, made of good heat-conducting material, copper for example, which is arranged in the mould, so as to be sunk in the plate in the moulding process. This tube is also fitted with an intake nozzle 11 and an air valve 12 at the exit, similar to those which have been described concerning Figs. 1 and 2.

In all cases, the path followed by the heating agent is made as sinuous as possible, so as to insure a heat distribution as fast and as even as possible.

As it has been mentioned above, it is practical to use, as heating fluid, the compressed air of which a constant use is made in moulding machines. The said compressed air may be pre-heated in various manners, but it has proved to be particularly advantageous to utilize a heating system constituted by an electric resistor, since this system can be used in all cases.

In the form of embodiment of a pre-heater illustrated in Fig. 5, this pre-heater is provided by a tube 13, covered with an insulating compound 14 and which is closed at its two ends by plugs 15 and 16 respectively, which are, for example, screwed on the tube 13. In this tube, an electric resistor 17, in the shape of a hairpin and of a known model is arranged. It can, for example, be constituted by a ferro-nickel wire coated and insulated and placed within a small metal tube.

A simple U shaped arrangement has been illustrated, but, as it will be understood, any similar arrangement may be considered, for example: double U, sinusoid, etc. This resistor is fixed on the lower plug 15 and bears two binding posts for the electric current. This plug comprises also an intake nozzle 20 connected to the compressed air conduit of the machine, and it is provided with a calibrated opening 21 for limiting the air intake speed which enters within the tube 13 and which expands in this tube. This air flows around the resistor 17, is heated and flows out through the nozzle 22 of the plug 16, this nozzle having preferably greater dimensions than the intake nozzle 20. This nozzle will be connected to the intake nozzle, such as 4 or 11, of the pattern-plate by a flexible conduit.

In the form of embodiment illustrated in Fig. 6, the air heater proper comprises also a tube 23, covered with an insulating covering 24 and which is also closed at its ends by plugs 25 and 26.

In this form of embodiment, the electric resistor is wound on an insulating core 27 of any suitable shape. This core is fixed in the plug 25, for example by means of nuts and bolts 28, 29. A binding post 30, for the electric current is provided in the plug 25, and the wire which has been wound on the core 27 issues outside through the

axial conduit 31 provided in this core, in order to end on the binding post 32 provided at the end of the said core.

The compressed air is admitted in the inner chamber 33 through the nozzle 34 fitted also with a calibrated opening 35. Deflecting partitions as in 36, 37, etc. force the air to follow the long path around the resistor before flowing out through the nozzle 38 mounted on the opposite plug 26.

It is to be understood that the constitution of the core 27 can be of any shape: plug, tube, plate or even a simple frame.

In the form of embodiment shown in Figs. 7 and 8, the electrical resistor 39, formed for example in the same manner as the resistor 17 of Fig. 5, is sunk in a tubular mass 40, for instance made of aluminium in the case where the resistor 39 itself is insulated. This mass 40 ends in a ring 41 and bears "in" and "out" binding posts 42, 43 for the electric current. The resistor thus formed is enclosed in a box 44, preferably coated with a coating of thermal insulating material 45. This box is closed by the ring 41 which bears against it and is retained by a plate 46 and a plate 47 positioned therebetween made of insulating material.

The plates 46 and 47 bear, naturally, drilled openings to pass the binding posts 42, 43. The whole assembly may be enclosed in a metal envelope 41a.

The tubular mass 40 comprises a plurality of drilled radial openings as shown in 48, 49. The compressed air is admitted through the nozzle 50 which passes through the bottom of the box and is provided with a calibrated opening 51. This air flows thus all along the resistor in the annular chamber 52 or inside the tubular mass 40, and flows out through the tube 53 which issues almost level with the openings 48 and is extended by the exit nozzle 54. In this manner, the air is in contact with the resistor for a considerable length of time.

This pre-heating device can be mounted on a plate 55 for its attachment to the moulding machine.

In the embodiment shown in Fig. 9, the heating resistor 56 is also wound in spiral form and sunk in an aluminium mass 57, this resistor being of the insulated type and placed within a metal tube. This mass 57 is equipped with blades 58 forming a continuous spiral. The overall shape is frustro-conical corresponding to a similar shape of the box 59, this insuring a sealing between these blades and this box. The air introduced through the nozzle 60 fitted with a calibrated opening 61 flows thus in spirals between these blades, around the mass 57. Then it passes through this mass through conduits as shown in 62, 63, 64, drilled at a place located the furthest from the intake nozzle and enters the central conduit 65 drilled in the mass 57, which issues outside where it reaches the exit nozzle 66.

In this embodiment also, the box 59 is coated with a layer of thermal insulating material 67, and the mass 57 ends in a circular plate 68 which engages frictionally in the free opening of the box 59. The two ends of the resistor which pass through this plate end externally at the binding posts 69 and 70 for connection to the electric current.

The assembly is made by means of the upper threaded end of the tube 65 on which the nozzle 66 is screwed, as shown at 71. A metal washer 72 presses on the lining 67 and consequently on

the bottom of the box, completing the assembly and insuring the tightness thereof.

Thus the electric resistor may be replaced simply by unscrewing the nozzle 66 and removing the wire from the binding posts. On the other hand, the calibrated part 61 is located in a plug 73 screwed in the intake nozzle 60, and is thus easily accessible, and can be cleaned with great facility.

Fig. 10 illustrates a moulding machine 74 on which is mounted a pattern-plate 75 formed as described in relation with Figs. 1 to 4.

The nozzle 4 or 11 of this plate 75 is connected through a flexible tube 76 to the air pre-heater 77 which is fixed on the column 78 of the machine, the intake nozzle of this pre-heater being connected by the tube 79 to the compressed air source. The pattern-plate is shown here in the moulding position.

In the form of embodiment shown in Fig. 11, the air pre-heater 80 is here fastened to the column and is connected, in the manner described relating to Fig. 10, to the pattern-plate 81, which in this case is a single surface plate. This plate 81 is insulated from the slab 83 of the machine by an asbestos plate 82.

Whichever form of embodiment of electric pre-heater is used, it is important that the electric current be switched off from the resistor when the heated fluid does not flow, for any reason, and to switch it on again only when the fluid has resumed its flow.

Fig. 12 shows a vertical cross-section of a device which automatically insures the opening and the closing of the electrical heating circuit, and is actuated by the pressure of the fluid conducting heat to the pattern-plates. This device adapts itself, without any changes being made, to any one of the pre-heating organs described above.

The admission of compressed air into the heating chamber is made through the feeding block 84, screwed on the lower part 85 of the heating resistor support. The air enters through the nozzle 86 screwed in the block 84, passes then into the transverse conduit 87 to the conduit 88 which issues into the heat chamber, passing through the calibrated opening 89.

In the conduit 87, a chamber 90 issues which is closed by a piston 91 the rod of which 92, protrudes outward from the block 84 and is urged toward the nozzle 86 by a spring 93.

The electric switch is here a mercury circuit breaker 94, the cradle of which is connected at 96 to a bracket 97 integral with the block 84. This cradle is pressed at its end 98, on the rod 92 by a spring 99 bearing on the support 85 of the resistor.

One of the supply wires 100, goes straight to one of the binding posts of the resistor, while the circuit breaker is inserted in the second wire 101.

In the example shown the air intake is interrupted and the electric circuit is open. When the compressed air is let in, it pushes back the piston 91 against the springs 93 and 99. The circuit breaker then rocks and the electric circuit is closed whereupon the resistor heats. If a new interruption occurs in the compressed air flow, the pressure in the conduit 87 decreases, the piston 91 and the circuit breaker are brought back to the position shown and the electric circuit is again open.

The above described assembly is advantageously protected by a jacket 102 extending towards the bottom from the metal washer 103 which, by

screwing onto the end 85 of the resistor support, closes the heat chamber.

The devices which have been described above therefore insure an individual pre-heating for each machine of the air utilized for the heating of the pattern-plate and thus insuring a great adaptability in the operation of the moulding installation.

The forms of embodiments hereinabove described are given as non-limitative examples, and modifications of details may be made without departing from the scope of the invention.

The air pre-heater, namely, could be of any type different from those hereinabove described, as long as it insures the pre-heating of the compressed air on each machine.

What I claim is:

1. An apparatus for the pre-heating of pattern-plates mounted on a moulding machine for the construction of sand moulds used in foundry work, which comprises, in combination with a moulding machine driven by compressed air and a pattern-plate, a conduit connected to said machine for receiving compressed air therefrom, an electric device for the pre-heating of the compressed air, a heat insulated container within which is arranged said electric device and connected to said conduit, an inlet and an outlet for the compressed air provided in said container and calibrated so as to permit an expansion of the compressed air in it, a heat exchange device disposed in the pattern-plate to be pre-heated, a further conduit connecting said heat exchange device to the outlet of said container, control means connected to said first mentioned conduit for receiving and being actuated by the compressed air therein and an electrical switch connected to the circuit of said electrical device for controlling the source of current thereto and to said control means for being actuated thereby and closing said circuit upon the passage of compressed air through said first mentioned conduit.

2. An apparatus for the pre-heating of pattern-plates mounted on a moulding machine for the construction of sand moulds used in foundry work, which comprises, in combination with a mould-

ing machine driven by compressed air, and a pattern plate, a conduit connected to said machine for receiving compressed air therefrom, an electric device for the pre-heating of the compressed air, a heat insulated container within which is arranged said electrical device, an inlet connected to said conduit and an outlet for the compressed air provided in said container and calibrated so as to permit an expansion of the compressed air in it, a heat-exchange device disposed in the pattern-plate to be pre-heated, a further conduit connecting said heat-exchanging device to the outlet of said container, a cylinder connected to said first conduit for receiving compressed air therefrom, a piston slidably mounted in said cylinder, resilient means positioned against said piston and in said cylinder, and a mercury switch connected to said electrical device for controlling the supply of current thereto and to said piston for being closed upon passage of compressed air and normally opened by said spring.
